United States Patent Office

Des. 231,160
Patented Apr. 9, 1974

231,160

BATH SLIPPER OR SIMILAR ARTICLE

Jean W. Schwarzenbach and Barbara J. Schwarzenbach, both of 1017 N. Knight, Park Ridge, Ill. 60068

Filed July 31, 1972, Ser. No. 276,516

Term of patent 14 years

Int. Cl. D2—04

U.S. Cl. D2—283

FIG. 1 is a perspective view of a bath slipper showing our new design;

FIG. 2 is a front elevational view thereof;

FIG. 3 is a side elevational view, the opposite side being a mirror image of the side shown;

FIG. 4 is a top plan view thereof;

FIG. 5 is a rear elevational view thereof; and

FIG. 6 is a bottom plan view thereof.

We claim:

The ornamental design for a bath slipper or similar article, as shown.
